UNITED STATES PATENT OFFICE.

LOUIS WOJIDKOW, OF BROOKLYN, NEW YORK.

DESIGN FOR A STAND FOR TEA-KETTLES.

SPECIFICATION forming part of Design No. 27,989, dated December 7, 1897.

Application filed October 20, 1897. Serial No. 655,855. Term of patent 3½ years.

To all whom it may concern:

Be it known that I, LOUIS WOJIDKOW, a citizen of the United States, residing at Brooklyn, county of Kings, and State of New York, 5 have invented and produced a new and original Design for a Stand for Tea-Kettles, of which the following is a specification, reference being had to the accompanying drawing, forming part thereof.

10 The drawing shows a perspective view of my new design for stands for tea-kettles.

As shown in the drawing, the leading or material feature of my design consists of a cross-bar at the upper ends of the supports of 15 the stand, upon which cross-bar are arranged armed arch-shaped bars.

10 A indicates the base of the stand, from diametrically opposite points of which rise outwardly-inclined supports B. These supports 20 are each formed of two uprights b b', curved

inwardly and spread outwardly at their lower and upper ends and connected near their lower ends by a loop or pretzel-shaped ornament C. The upper ends of the uprights b b' are formed with volutes b² and are connected 25 by a studded cross-bar D, upon which is mounted an arch-shaped bar E, formed with volute feet e where the arch joins the cross-bar and with volute side arms e'.

Having thus described my invention, what 30 I claim is—

The design for a stand for tea-kettles, substantially as herein shown and described.

In testimony that I claim the foregoing as my invention I have signed my name in presence of two subscribing witnesses.

LOUIS WOJIDKOW.
